US00D962956S

(12) **United States Design Patent** (10) Patent No.: **US D962,956 S**
Chaudhri et al. (45) Date of Patent: ** Sep. 6, 2022

(54) DISPLAY SCREEN OR PORTION THEREOF WITH GRAPHICAL USER INTERFACE	5,736,099 A	4/1998	Hiraide et al.
(71) Applicant: Apple Inc. , Cupertino, CA (US)	5,896,133 A	4/1999	Lynch et al.
(72) Inventors: Imran Chaudhri , San Francisco, CA (US); Christopher Foss , San Francisco, CA (US); Mini Ham , Seoul (KR); Jonathan P. Ive , San Francisco, CA (US); Chanaka Karunamuni , San Jose, CA (US); Kenneth Kocienda , San Jose, CA (US); Christopher Wilson , San Francisco, CA (US)	5,986,654 A	11/1999	Alexander et al.
	5,989,200 A	11/1999	Yoshimura et al.
	6,009,444 A	12/1999	Chen
	D418,826 S	1/2000	Pavely et al.
	6,073,036 A	6/2000	Heikkinen et al.
	6,104,396 A	8/2000	Hanaoka et al.
	6,147,686 A	11/2000	Brown et al.
	6,182,287 B1	1/2001	Schneidewend et al.
	6,211,856 B1	4/2001	Choi et al.
	6,222,538 B1	4/2001	Anderson
	6,229,532 B1	5/2001	Fujii
	6,229,603 B1	5/2001	Coassin et al.

(57) CLAIM

The ornamental design for a display screen or portion thereof with graphical user interface, as shown and described.

DESCRIPTION

The file of this patent contains at least one drawing/photograph executed in color. Copies of this patent with color

drawing(s)/photograph(s) will be provided by the Office upon request and payment of the necessary fee.

FIG. 1 is a front view of a display screen or portion thereof with graphical user interface showing the claimed design;

FIG. 2 is a second embodiment thereof;

FIG. 3 is a third embodiment thereof; and,

FIG. 4 is a fourth embodiment thereof.

The outermost broken lines in the figures show a display screen or portion thereof, and form no part of the claimed design. The other broken lines in the figures show portions of the graphical user interface that form no part of the claimed design.

1 Claim, 2 Drawing Sheets
(2 of 2 Drawing Sheet(s) Filed in Color)

FIG. 1

FIG. 2

FIG. 3

FIG. 4
